DOOR CHECK AND CLOSER

Forrest C. Garrison, Chicago, Ill., assignor to
The Oscar C. Rixson Co., Chicago, Ill., a corporation of Illinois

Application August 15, 1935, Serial No. 36,359

7 Claims. (Cl. 16—62)

This invention relates to door checks and closers of the sealed type in which the operating mechanism is located in the head jamb above the door and is connected to the door by an arm 5 having a slide at the door end of the arm which slide travels in a guide rail countersunk in the top of the door.

A purpose of the invention is to improve such constructions by an arrangement of separate 10 checking and spring-operated closing units, each having its own spindle in a way to allow compactness while still permitting the use of large and durable operating elements.

It is also a purpose of the invention to provide 15 a simplified adjusting means for regulating the closing mechanism of a door and also in utilizing the closing spring for maintaining tightness in a packing at the end of a cylinder.

In the accompanying drawings illustrating the 20 new construction,

Figure 1 is a fragmentary view, in elevation, of a door and a head jamb thereover having the door check and closer mounted therein. In this view part of the door and head jamb is shown 25 in section.

Fig. 2 is a sectional view through the door looking upwardly as indicated by the line 2—2 of Fig. 1.

Fig. 3 is a sectional view taken on the line 3—3 30 of Fig. 1 through the door and head jamb showing in end elevation the door check and closer casing with the improved adjusting means thereon.

Fig. 4 is a longitudinal section of the door 35 closer and check.

Fig. 5 shows a plan view of the door closer and check with part of the casing in section and the cover plate removed.

Fig. 6 is a transverse sectional view of the 40 mechanism as indicated by the line 6—6 on Fig. 5.

Fig. 7 is an end view of the door closer and check.

This door check and closer is like others in 45 the same class in making use of a cylinder mounted within the head above a door and having a plunger, or plungers, which check movement of the door and also having a spring associated with the plunger for impelling the door to closed position; but in the present arrangement it is intended to make such constructions more satisfactory as to durability, reliable performance, compactness, regularity of outside dimensions and ease of installation. There are two cylinders and pistons, each piston being 50 connected to a separate spindle mounted in sub-

stantial roller bearings, each having a segment gear connection to a third or main spindle which carries an operating arm connecting the main spindle with a slide on the top of the door.

The closing spring bears at one end against 5 one of the pistons and at its opposite end bears against a non-rotary seat but which is free to move lengthwise in the cylinder as adjusted by a screw element passing therethrough. This spring seat transmits thrust to the screw which 10 in turn bears against a packing gland which tightly presses a packing around the shank of the screw. The screw passes through the end of the cylinder and has a head to permit easy adjustment from the outside. 15

In the drawings, a casing 1 for the operating mechanism is a single casting including cylinders 2 and 3 and an intermediate rectangular frame part 4 formed to support a main operating spindle 5 and spindles 6 and 7. The main spindle 20 5 passes through roller bearings 8 and 9 fitting within receiving bosses formed in part 4 of the casting. The spindles 6 and 7 have similar mountings within roller bearings 10 and 11.

Attached to the lower squared end 12 of spindle 25 5 is an arm 13 which carries at its outer end on a ball pivot 14 (Fig. 4) a slide 15 fitting a guide rail 16 which is countersunk in the upper part of the door frame 17, as indicated in Figure 3.

By the act of opening the door, the arm 13 30 swings out with the door, while the slide 15 moves toward a limiting stop consisting of cushion springs 18 carried by pins 19 projecting from a fixed block 20 at the end of rail 16.

During an opening movement of the door, the 35 spindle 5 turns in its bearings and through a pinion 21 secured to the top of the spindle transmits motion through gearing sectors 22 and 23 to the spindles 6 and 7. Spindle 6 has a squared central portion 24 for rigidly carrying a crank arm 25, by 40 means of which motion is transmitted through a connecting rod 26 to a piston 27 operating in the cylinder 2.

The rate of movement of the piston 27 is regulated by oil resistance controlled by a check valve 27.1 in the piston and two regulating valves 29 and 29.1 (Figure 2) which respectively adjust and control the flow of oil in the by-pass ducts 29.2 and 29.3 leading around the piston in a boss 30 located at the side of the cylinder. All parts of the construction are designed to minimize backlash and the spring 31 between the piston 27 and the cylinder cap 28 is for that purpose. 45

The cylinder 3 on the opposite side of the gear 50 casing is for containing spring 32 which spring 55

receives energy on the opening movement of the door through the piston 33 which slides in the cylinder 3 because of its link connection 34 to arm 35 on the spindle 7. When the door is released, the spring closes the door through these connections. At its right-hand end (Fig. 5) spring 32 bears against a flanged nut 36 which fits a screw 37 and may be adjusted along the screw by rotating the latter at which time the turning of nut 36 is prevented by a pin 38 which projects from the side of the nut into a groove 39 on the inner surface of the cylinder.

The pressure of the spring is, through the nut, exerted endwise on screw 37 and this thrust is utilized to keep packing 40 tightly fitting against a round shank 41 of the screw which passes through the cylinder end cap 42. The screw carries a washer 43 which bears against the packing.

20 There is a spring adjuster disc 44 fast to the flattened end 45 (Fig. 7) of the shank of the screw. Disc 44 has peripheral cuts 46 to facilitate rotation of the screw as by means of a screw driver. Access to the disc may be had after installation of the construction by releasing finishing plate 47 at the bottom of the casting through removal of screws 48 which hold the plate in place. The casting is attached to the frame structure of head 49 (Fig. 1), by screws 50 which are normally covered by the plate 47.

The door 17 (as shown in Fig. 3) is recessed along its upper edge to receive the track 16 within which slide block 15 slides.

In the operation of this door closing and checking construction, the door is manually swung outwardly on its hinges 51, as illustrated by Fig. 2. This motion causes the arm 13 to rock outwardly from the position parallel with the closed door and as the angular relationship 40 changes, the slide 15 travels along guide rail 16 toward the springs 18 (Fig. 1) therein which serve as a final cushion and stop for the door.

Upon the opening movement, the rotation of spindle 5 which is fast to the arm 13, is such as 45 to move sector gear 22 in the direction of the arrow marked thereon. This causes the piston 21 to move to the right. The oil which nearly fills the casing goes past the check valve 27 to the opposite side of the piston; thus excessive 50 rate of movement of the door is checked. At the same time, through the sector gear 23 and connections with piston 33, the spring 32 is compressed to store up power for closing the door; but springs 31 and 32 are normally under some 55 compression when the door is in its closed position and by acting in opposite directions serve to remove all backlash from the mechanism.

Spring 32 is at all times under compression and there is no chance for free play to occur in the 60 construction. The separate spindles 6 and 7 are advantageous in this connection, each being a part of its own unit for respectively checking and closing.

The use of separate spindles 6 and 7 also enables the use of a narrow and symmetrical casing for the mechanism and the use of heavy parts within desirable dimensions.

Should it be desirable to increase or decrease the tension of spring 32, the flanged nut 36 is 70 shifted lengthwise of the casing in either direction by turning the adjuster 44 which serves to rotate the screw 37 which meshes with the nut. Rotation of the nut is prevented by the pin guide 38.

75 Although but one specific embodiment of this

invention is herein shown and described, it is to be understood that details as set forth may be altered or omitted without departing from the spirit of the invention as defined by the following claims:

I claim:

1. An overhead door checking and closing mechanism comprising a frame structure adapted to fit lengthwise in the head jamb over a door which frame structure is formed to provide 10 a pair of opposed cylinders with an intermediate gear casing, said gear casing having journaled therein three vertical spindles, one of said spindles having an arm fixed thereto with a door connection at its opposite end whereby said spindle will be turned when the door is opened, said one spindle having gear connections with each of the other two spindles, a plunger in each of said cylinders, said other two spindles being each linked to one of said plungers, and a spring for 20 resisting the motion of one of said plungers.

2. An overhead door checking and closing mechanism comprising a frame structure adapted to fit lengthwise in the head jamb over a 25 door which frame structure is formed to provide a pair of opposed cylinders with an intermediate gear casing, said gear casing having journaled therein three vertical spindles, one of said spindles having an arm fixed thereto with a door connection at its opposite end whereby said 30 spindle will be turned when the door is opened, said one spindle having gear connections with each of the other two spindles, a plunger in each of said cylinders, said other two spindles being each linked to one of said plungers, a spring 35 for resisting the motion of one of said plungers, a spring adjuster comprising a spring seat which is mounted for sliding motion lengthwise of the cylinder but against rotation, a screw threaded through said spring seat and passing through 40 the head of the spring cylinder, and an adjusting means attached to the screw exteriorly of the cylinder.

3. An overhead door checking and closing mechanism comprising a frame structure adapted 45 to fit lengthwise in the jamb over a door which frame structure is formed to provide a pair of opposed cylinders with an intermediate gear casing, said gear casing having journaled therein three vertical spindles, one of said spindles having an arm fixed thereto with a door connection at its opposite end whereby said spindle will be turned when the door is opened, said one spindle having gear connections with each of the other 50 two spindles, a plunger in each of said cylinders, said other two spindles being each linked to one of said plungers, a spring for resisting the motion of one of said plungers, a spring adjuster comprising a spring seat which is mounted for 55 sliding motion lengthwise of the cylinder but against rotation, a screw engaging said spring seat and passing through the head of the spring cylinder, and an adjusting means attached to the shank of the screw exteriorly of the cylinder.

4. An overhead door checking and closing mechanism comprising a frame structure adapted to fit lengthwise in the jamb over a door which frame structure is formed to provide a pair of opposed cylinders with an intermediate gear casing, said gear casing having journaled therein three vertical spindles, one of said spindles having an arm fixed thereto with a door connection at its opposite end whereby said spindle will be turned when the door is opened, said one spindle 70 having gear connections with each of the other 75

- two spindles, a plunger in each of said cylinders, said other two spindles being each linked to one of said plungers, a spring for resisting the motion of one of said plungers, a spring adjuster comprising a spring seat which is mounted for sliding motion lengthwise of the cylinder but against rotation, a screw engaging said spring seat and passing through the head of the spring cylinder, an adjusting means attached to the shank of 5 the screw exteriorly of the cylinder, a packing between said screw and the head of the cylinder, and means on the screw for compressing the packing by the thrust on the screw transmitted from the spring through the spring seat.
- 10 5. A door check mechanism of the class described comprising a spring cylinder, a compression spring within said cylinder, means for transmitting motion between a door and said spring, a spring adjuster comprising an element mounted within said cylinder and forming a seat 15 for the spring, means for preventing rotation of said element, means for adjusting said element lengthwise of the cylinder consisting of a screw having threaded engagement with said element, said screw having a shank passing through the head of the cylinder, a screw-operating means on the end of the shank, and a compression packing between the screw and the head of the cylinder which receives thrust from said spring 20 through the spring adjusting element and the screw.
- 25 6. A door check mechanism comprising a frame structure adapted to fit in the head jamb over a door and which frame is formed to provide a pair of cylinders and a gear casing, a main spindle journaled in said frame, an arm cooperating with said main spindle and connected to the door whereby said main spindle turns when the door swings, a pair of secondary spindles connected with said main spindle for simultaneous rotation, a dash-pot plunger having pitman connection to one of said secondary spindles, a door closing spring having a sliding head 25 with pitman connection to the other of said secondary spindles, and a spring coacting with said plungers and coacting with said door closing spring to take up all backlash in said connections. 30
7. A door check mechanism comprising a frame structure adapted to fit in the head jamb over a door and which frame is formed to provide a pair of cylinders and a gear casing, a main spindle journaled in said frame, an arm cooperating 20 with said main spindle and connected to the door whereby said main spindle turns when the door swings, a pair of secondary spindles geared to said main spindle for simultaneous rotation, a dash-pot plunger having pitman connection to one of said secondary spindles, a door closing spring having a sliding head with pitman connection to the other of said secondary spindles, and a spring coacting with said plunger and coacting with said door closing spring to take up all backlash in said connections. 35

FORREST C. GARRISON.
